BY

UNITED STATES PATENT OFFICE.

HUGO OPPERMANN, OF PHILADELPHIA, PENNSYLVANIA.

EGG-TESTER.

SPECIFICATION forming part of Letters Patent No. 371,517, dated October 11, 1887.

Application filed March 19, 1887. Serial No. 231,556. (No model.)

To all whom it may concern:

Be it known that I, HUGO OPPERMANN, a citizen of the United States, residing in the city and county of Philadelphia, State of Pennsylvania, have invented a new and useful Improvement in Egg-Testers, which improvement is fully set forth in the following specification and accompanying drawings, in which—

Figure 1 represents a side elevation of an egg-tester embodying my invention. Fig. 2 represents a top view thereof. Fig. 3 represents a vertical section thereof. Figs. 4 and 5 represent views of detached portions.

Similar letters of reference indicate corresponding parts in the several figures.

My invention consists of an egg-tester having a novel support for the mirror.

It also consists of an egg-tester having a lamp for illuminating the eggs.

Referring to the drawings, A represents the body of the egg-tester, the same being formed of metal or other suitable material, preferably of conical shape, the top of the body being open and provided with a flaring rim, B, to sustain an egg while being tested. To the side of the body is secured an eye-piece, C, which is set at an inclination, so that the eye may be properly directed to the mirror D within the body A.

The mirror is supported on the base-piece E, which is removably fitted to the bottom of the body, and has secured to it a pin, E', which is adapted to enter an L-shaped slot, F, in the body, thus connecting the base and body by a bayonet-joint.

The mirror is inclined and has its lower end resting on the bottom of the base and its high end supported on a lip, G, which is cut out of the side of the base. Lips H are also cut out

of the side of the base and bent down on the mirror, the latter thus being clamped between the lips G H and prevented from displacement.

Secured to the body A is a lamp, J, whose top is adjacent to the rim B of the body A, so that the flame of the lamp may rise sufficiently to illuminate the egg resting on said rim. The conical shape of the body is of advantage, as it permits the construction of the lamp J on the side of the body A and within the line of the base, thereby rendering the device stable and not liable to overturn or upset.

The lamp will be found serviceable for testing eggs at night and during day-time when there is not sufficient light.

The manner of testing an egg is by reflecting the same on the mirror D, the good or bad quality of the egg being apparent by the nature of the reflection on said mirror.

Having thus described my invention, what I claim as new, and desire to secure by Letters Patent, is—

1. An egg-tester having a conical body with the flaring rim B at the top thereof and the lamp J on the side of the body and within the line of the base, and having its burner adjacent to the said flaring rim, substantially as and for the purpose set forth.

2. An egg-tester composed of the body A, with top opening, B, and inclined eye-piece C at the side of said body, the removable base E, with lip G, and the inclined mirror D, the mirror resting on said lip G, said parts being combined substantially as and for the purpose set forth.

HUGO OPPERMANN.
